METAL CONTAINER

Charles E. McManus, Spring Lake, N. J., and
Wittie I. Gladfelter, Philadelphia, Pa., assignors
to Crown Cork & Seal Company, Inc., Balti-
more, Md., a corporation of New York

Application April 27, 1942, Serial No. 440,672

6 Claims. (Cl. 220—48)

The present invention relates to metal containers such as are employed for beverages, medicines, chemicals, foodstuffs, and other similar types of commodities.

An object of the invention is the provision of a container of this character in which the top is provided with an integral end or closure having a scored or weakened area capable of being ruptured or severed by a can opening tool.

A further object is to provide a metal container having an integral or non-removable closure provided with a score line or analogous weakened portion formed in the top surface thereof and substantially enclosing a portion of the closure but leaving an unscored section between the ends of the score line. Associated with the score line is an indented recess located below and in line with the unscored section of the closure and constituting a guide and fulcrum point for receiving an end of a can opening tool whereby the tool may be quickly and accurately applied to the can to rupture the weakened area within the score line and permit discharge of the contents of the container.

Another object is the provision of a container of this character having a neck integrally connected to the scored closure, said neck being provided with an indented recess and also having a screw threaded area either above, below or within the confines of the recess, whereby a threaded closure may be applied to the neck subsequent to the rupturing of the integral closure to permit resealing of the container.

With the foregoing and other objects in view, the invention will now be more particularly described, reference being had to the accompanying drawings in which:

Figure 1 is a side elevation of one embodiment of the present invention.

Figures 2 and 3 are top and bottom plan views respectively of Figure 1.

Figure 4 is an enlarged vertical section of the container shown in Figure 1.

Figure 4a is a fragmentary view of the top and bottom sections of a pair of cans showing them in nested relation.

Figure 5 is a modification showing a vertical section through the top portion of the container and in which a screw threaded neck is provided.

Figure 5a shows a screw threaded closure to be applied to the neck of the container shown in Figure 5.

Figure 6 is a further modification in which threads on the neck terminate below the top of the same.

Figure 7 is another modification in which the threads on the neck terminate above the bottom of the neck.

Figure 8 is a further modification in which the neck is designed to receive a cap of the crown type.

Figure 8a is a crown cap to be applied to the neck of the container shown in Figure 8.

Figure 9 is a further modification showing the can body, top and closure made from a single piece of material, and

Figure 10 is an enlarged fragmentary view through a portion of the top of the container to show the scoring.

10 15 Containers in accordance with the present invention are preferably constructed of relatively thin sheet metal, such as tin plate or steel. Referring to Figures 1 to 4a there is disclosed one embodiment of the present invention in which the numeral 10 designates generally the container having a body 11 of substantially cylindrical formation, a top 12 and a bottom 13. Both the bottom and top are preferably secured to the body by the usual double seam joint.

20 25 The top 12 is formed from a single blank and consists of a tapered or frusto-conical portion 14, a centrally disposed integral neck 15, and a closure 16 integral with the neck. Referring particularly to Figures 1 and 4, it will be observed that the closure 16 merges into the neck and is substantially flat within the confines of the same, presenting a continuous uninterrupted top surface. This top surface of the closure is scored to form a circular score line 17 which substantially encloses a portion of the closure but leaves an unscored section between the ends of the score line. That is, the ends 18 of the score line terminate at spaced points (see Figure 2) to provide an unscored section 19 which constitutes a hinge 30 35 to permit the circular scored or weakened area to be bent down within the neck when the closure is ruptured. It is to be understood that while the score line 17 has been described as being substantially circular in formation, the invention is not limited to any specific configuration or formation so long as the score line encompasses an area which can be ruptured and depressed to provide a pouring opening in the closure.

40 45 The neck 15 is provided with an indented recess 20 slightly below the top thereof and below the score line, and which is in direct alignment with the unscored section 19 of the closure. This recess constitutes a guide and fulcrum point for a can opening tool 21 shown in dotted lines in Figure 4. While any particular type of can open-

ing tool may be utilized, the one shown in the drawings and designated by the numeral 21 is preferred, since it is particularly adapted to quickly and easily rupture the closure 16. Tool 21 is provided with a shank 22, a lug 23, and a hooked top portion 24 terminating in a substantially blunt end 25, the latter being adapted to be received within the indented recess 20.

With a container having a top and integral closure constructed as shown in Figures 1 to 4, the closure may be easily and quickly ruptured by applying the tool 21. In view of the fact that the indented recess 20 is located below the score line 17 and in line with the unscored portion 19, the tool may be quickly and accurately applied to the neck and closure of the container in the position shown in dotted lines in Figure 4. In this position, it will be noted that the lug 23 is in contact with the top surface of the closure just within the score line and at a point diametrically opposite the unscored section 19. By applying downward pressure on the shank 22 the tool will easily rupture the portion of the closure within the score line 17 and bend this portion downwardly within and to one side of the neck 15 to form a pouring opening to permit the contents of the container to be discharged therefrom.

It is to be understood that the opening tool 21 is merely representative of one type of tool which may be utilized in rupturing the closure 16. The present container is also designed to accommodate the type of open tool wherein the hook which engages the indented recess 20 is located intermediate the end of the shank and in which the end of the tool will contact the weakened area of the closure in place of the lug 23.

It will be observed that the bottom 13 of the container is of concave formation which strengthens the container to resist high internal pressures. Furthermore, since the neck 15 and closure 16 are of reduced height, the concaved bottom provides a space which permits the top of one container to be compactly nested into the bottom 13 of an adjacent container (see Figure 4a).

Referring now to Figures 5 and 5a, the container top 26 is formed with a conical portion 27 merging into a neck 28 which is of greater height than the neck 15 of the embodiment shown in Figures 1 to 4. This neck is formed integrally with a closure 29 provided with an interiorly arranged slightly depressed area 30. This area is formed with a score line 31 similar to the score line 17 in that the ends of the score line terminate at spaced points to provide an unscored section. An indented recess 32 is formed in the neck below the closure and score line and in line with the unscored portion of the closure for the same purpose as that described above with respect to Figures 1 to 4. This type of container is designed so that it may be resealed and used subsequent to the rupturing of the integral closure 29. In this connection the neck is provided with a screw thread 33 which passes through the area of the recess 32. However, the screw threads do not interfere with the function of the recess, nor does the recess interfere with the function of the screw thread. In other words, after the closure 29 has been ruptured by a can opening tool to depress the weakened area, a screw closure 34 is adapted to be applied to the neck and screwed down upon the screw thread 33 to provide a tight and effective seal for the contents of the container. It will

be observed that the depressed area 30 forms an annular flat surface 30' which cooperates with the closure 34 to provide an effective seal.

Figure 6 illustrates a further modification which differs from that shown in Figure 5 in that the neck 35 is provided with a screw thread 36 terminating below the indented recess 37. That is, the recess 37 is above and entirely clear of the screw thread 36. As in the form shown in Figure 5, the recess 37 does not interfere with the function of the thread 36 and the efficiency of each is not affected by the relative position of the other.

Figure 7 shows an additional modification in which the neck 38 is provided with a screw thread 39 terminating above the lower end of the neck and also above the indented recess 40. Thus, in this arrangement as in the forms shown in Figures 5 and 6, the indented recess does not interfere with the function of the screw thread 39. It is to be understood, of course, that with each different construction it may be necessary to change the contour of the opening tool so that the hooked end and the lug will be correctly proportioned to accommodate the particular recess and closure. In other words, the hooked end portion of the opening tool shown in Figure 2 must necessarily be somewhat enlarged to accommodate the modification shown in Figure 7 wherein the recess 40 is at a greater distance from the top of the neck than that disclosed in Figure 2.

Figure 8 shows a modification which is particularly adapted to accommodate the usual crown cap. In this arrangement the neck 41 is provided with a reduced area or ring 42 directly below the integral closure 43. The indented recess 44 is located within the area of the reduced ring 42 but does not in any manner impair or interfere with the sealing functions of the crown cap 45 which is adapted to be applied to the neck after the scored portion of the integral closure 43 has been ruptured.

Figure 9 illustrates an additional modification which is quite similar to that shown in Figures 1 to 4, except that the body 46, conical top 47, neck 48 and closure 49 are all formed from a single piece of material. The means for effecting rupture of the container are the same as those described above, in that the closure 49 is provided with a substantially circular score line 50 and an indented recess 51 which is below and in line with the unscored portion of the closure.

It is to be understood that the form of the invention shown and described is illustrative of the preferred embodiment and that such changes may be made without departing from the spirit of the invention as fall within the purview of one skilled in the art and the scope of the appended claims.

We claim:

1. A metal container having a top provided with a neck, a closure integral with the neck, and a score line formed in the top surface of the closure and substantially enclosing a portion of the closure but leaving an unscored section between the ends of the score line, said neck having an indented recess below and in line with the unscored section of the closure, the side walls of said recess terminating substantially within the confines of the unscored section whereby the recess constitutes a guide and fulcrum point for a can opening tool.

2. A metal container having an integral top, a score line formed in the top and substantially

enclosing a portion thereof but leaving a small unscored section between the ends of the line, said container having an indented recess below and in line with the unscored section of the closure, the side walls of said recess terminating substantially within the confines of the unscored section whereby the recess constitutes a guide and fulcrum point for a can opening tool.

3. A metal container having a top provided with a neck, a closure integral with the neck, a score line formed in the top surface of the closure and substantially enclosing a portion of the closure but leaving a small unscored section between the ends of the score line, said neck having a screw thread terminating below the top of the neck and adapted to receive a screw threaded closure, said neck having an indented recess located between the screw thread and closure and in line with the unscored section of the closure, the side walls of said recess terminating substantially within the confines of the unscored section whereby the recess constitutes a guide and fulcrum point for a can opening tool.

4. A metal container having a top provided with a neck, a closure integral with the neck, a score line formed in the top surface of the closure and substantially enclosing a portion of the closure but leaving a small unscored section between the ends of the score line, said neck having a screw thread extending to the top of the neck and adapted to receive a screw threaded closure, said neck having an indented recess located in the screw thread below and in line with the unscored section of the closure, the side walls of said recess terminating substantially within the confines of the unscored section of the closure.

5. A metal container having a top provided with a neck, a closure integral with the neck, a score line formed in the top surface of the closure and substantially enclosing a portion of the closure but leaving a small unscored section between the ends of the score line, said neck having a screw thread extending downwardly from the top of the neck and terminating above the lower portion of the neck, said neck having an indented recess located below the screw thread and in line with the unscored section of the closure, the side walls of said recess terminating substantially within the confines of the unscored section whereby the recess constitutes a guide and fulcrum point for a can opening tool.

6. A metal container having a top provided with a neck, a closure integral with the neck, a score line formed in the top surface of the closure and substantially enclosing a portion of the closure but leaving a small unscored section between the ends of the score line, said neck having a reduced ring directly below the closure to form a cap receiving bead, said neck having an indented recess located in the area of the reduced ring and in line with the unscored section of the closure, the side walls of said recess terminating substantially within the confines of the unscored section whereby the recess constitutes a guide and fulcrum point for a can opening tool.
